UNITED STATES PATENT OFFICE.

SEWARD E. COGSWELL, OF CENTRAL CITY, NEBRASKA.

AUTOMATIC SAMPLER.

1,241,196.

Specification of Letters Patent. Patented Sept. 25, 1917.

Application filed June 13, 1916. Serial No. 103,506.

To all whom it may concern:

Be it known that I, SEWARD E. COGSWELL, a citizen of the United States, residing at Central City, in the county of Merrick and State of Nebraska, have invented certain new and useful Improvements in Automatic Samplers; and I do hereby declare the following to be a full, clear, and exact description of the invention, such as will enable others skilled in the art to which it appertains to make and use the same.

This invention relates to an automatic sampler, and has for one of its objects the provision of a sampling device which can be readily attached to any spout for taking a sample of any grain, crushed material, or granulated substance that is being conducted through the spout by gravity.

Another object is the provision of means for taking a plurality of samples of the grain, crushed material, or granulated substance as the same is conducted through the spout.

A further object is the provision of means for successively taking a sample of the material traveling through the spout at any desired periods of time during the conducting, crushing, or grinding operations.

A still further object is the provision of a sampling device consisting of few parts and simple in construction, efficient in operation, and which can be manufactured and sold upon the market at a nominal cost.

These and other objects and advantages of this invention will more fully appear as the nature of the invention is more clearly understood from the following specification, the subject matter of the claims, and the views illustrated in the accompanying drawings, in which,

Figure 1 is a fragmentary perspective view of a spout showing the invention in applied operative position upon the under side of the spout.

Fig. 2 is a vertical longitudinal sectional view, through a portion of the spout and the sampler, showing the detail constructions thereof.

Fig. 3 is a vertical transverse sectional view on line 3-3 of Fig. 2 looking in the direction of the arrow, showing one position of the locking and releasing bar em-

ployed to provide for the intermittent movement of the sampler.

Fig. 4 is a similar view, partly broken away, showing another position of the locking and releasing bar employed.

Fig. 5 is a view similar to Fig. 4, but showing the locking and releasing lever in neutral position.

Fig. 6 is a fragmentary side view of the sliding tray employed showing the provision of the flange and the stop lugs thereon.

Fig. 7 is a fragmentary bottom plan view of the tray, showing the manner of forming the stop lugs from the bottom thereof.

Fig. 8 is a detail view of the means employed for actuating the locking and releasing bar at desired periods of time.

Referring to the drawings, wherein similar reference characters denote corresponding parts throughout the several views, 1 denotes the usual spout employed, for conducting the grain, or crushed materials, or granulated or comminuted substances, which is preferably rectangular in cross section, 2 denotes the transverse slot or opening formed in the bottom wall of the spout, the upper side wall of the slot or opening 2 being formed substantially at right angles to the inner surface of the bottom of the spout, while the lower side wall of the slot or opening 2 is formed obliquely in acute angular relation to the inner surface of the bottom so that the outlet end of the slot or opening 2 will be of much greater width than the inlet end of the slot or opening 2 to prevent the material from becoming clogged in the slot or opening 2 thereby choking the same.

Secured upon the under side of the spout 1 is the casing or jacket 3 having a bottom and side walls, the upper portions of the side walls being bent inwardly in their longitudinal direction, and thence bent outwardly in lapped relation to form the ribs 4, and thence upwardly to provide the attaching flanges 5 which are secured to the sides of the spout 1 adjacent its bottom by the nails or screws 6 which pass through apertures formed in the flanges 5 of the casing 3 and into the spout 1. The casing 3 is provided at its upper end with the inlet door 7, hinged to the bottom of the casing 3 at 8

and retained in closed position upon the casing 3 in any suitable manner by the spring catch 9, and also provided at its lower end with the outlet door 10, hinged to the bottom of the casing 3 at 11, and also secured in closed position in any suitable manner as by the spring catch 12. The casing 3 is also provided with the central door 13 in its bottom, hinged at its lower edge to the bottom of the casing 3 at 14, and secured in closed position within the bottom of the casing 3 by any suitable means as by the spring latch 15, and at one side of the casing 3 substantially centrally thereof is the housing 16 provided with the door 17, hinged to the housing 16 as at 18, and retained in closed position upon the housing 16 in any suitable means as by the spring latch 19.

Slidably mounted within the casing 3 is the tray comprising the bottom 20 the sides 21 formed substantially in the shape of a parallelogram, and the end walls 22. The upper edge of the sides 21 of the tray are bent outwardly at substantially right angles to the sides 21 to provide the flanges 23 for engaging the upper surfaces of the ribs 4 upon the inner side of the side walls of the casing 3 and adapted to slide thereon. The tray is suspended within the casing 3 with its bottom 20 in spaced relation to the bottom of the casing 3, and formed upon the bottom 20 of the tray at one side edge are the longitudinally alined stop lugs 24, and also upon the bottom 20 of the tray at the opposite edge thereof is formed the longitudinally alined stop lugs 25. The lugs 24 and the lugs 25 are cut and struck up from the bottom 20 of the tray and are of substantially triangular shape and formed in such a manner that the straight faces of the lugs are disposed at right angles to the bottom 20 and face downwardly. The lugs 24 at one side of the bottom 20 of the tray and the lugs 25 at the opposite side thereof are disposed in staggered relation to each other in the transverse direction of the bottom 20 of the tray.

The stop lugs 24 and 25 of the tray are alternately engaged and subsequently released by the reciprocating locking and releasing bar 26 which operates within the bottom portion of the casing 3 and travels in and projects through the elongated apertures 27 formed in the side walls of the casing 3 in proximity to the bottom thereof and disposed in right angular relation thereto. The locking and releasing bar 26 is of greater width than thickness and has formed in its upper edge adjacent its outer end the slot or gain 28, and also the slot or gain 29 adjacent its inner end, the slots or gains 28 and 29 are spaced apart at a less distance than the transverse distances between the stop lugs 24 and the stop lugs 25 for

locking and releasing the respective stop lugs in accordance with the positions of the locking and releasing bar 26 and the slots or gains 28 and 29 thereof. The locking and releasing bar 26 is of sufficient length to remain slidably within the apertures 27 formed in the side walls of the casing 3, and for reciprocating the bar 26 there is pivotally connected to the inner end of the bar 26 as at 30 one end of the connecting rod 31, having its opposite end pivotally connected to the wrist pin 32 of the driving wheel or disk 33 operatively mounted at the outer side of one of the side walls of the housing 16 and having its shaft 34 projecting through and revolvably mounted in the wall of the housing 16 and also revolvably mounted in the journal bracket 35, or other suitable means, the shaft 34 being provided upon its inner end with the removably secured worm wheel 36 which is driven by the worm 37 removably secured upon the end of the worm shaft 38 which worm shaft is adapted to be driven by any suitable time mechanism to be hereinafter stated.

The sliding tray within the casing 3 is provided with the plurality of removable sample receptacles or boxes 39. The receptacles or boxes 39 are rectangular and have a greater width than thickness, and preferably a greater length than width, and are provided with the open upper ends 40 which are beveled in one direction at substantially forty-five degrees or in a manner to snugly engage the under surface of the bottom of the spout 1. The interior transverse dimensions of the receptacles or boxes 39 are approximately the same as the dimensions of the discharged end of the opening 2 formed in the bottom of the spout 1, and for positioning a receptacle or box immediately beneath the slot or opening 2 of the spout 1 the stop lugs 24 and 25 upon the bottom 20 of the tray are so arranged that there is a lug in substantially vertical alinement beneath each of the receptacles 39, and the locking and releasing bar 26 operates through the bottom portion of the casing 3 at a point substantially in vertical alinement with the opening 2 in the bottom of the spout 1, whereby when one of either the lugs 24 or 25 engages the upper edge of the bar 26 there is positioned beneath and in registration with the opening 2 of the spout 1 the open beveled end 40 of one of the sample receptacles or boxes 39 which now remain stationary for receiving a proportion of the material traveling through the spout 1 through the opening 2 until the receptacle or box is filled, when the material traveling through the spout 1 ceases to flow into the receptacle 39 until the next succeeding empty receptacle 39 is positioned beneath the opening 2 of the spout 1 by the move-

ment of the bar 26 for releasing the lug engaging the bar through one of the slots or gains therein upon the movement of the bar 26 and locking the next succeeding oppositely staggered lug upon the tray for stopping the movement thereof.

The operation of the device is briefly described as follows:

The tray, containing a plurality of the sample receptacles or boxes 39 in juxtaposition to each other as shown in Fig. 2, is inserted through the upper door 7 into the casing 3 with the flanges 23 of the tray resting upon the ribs 4 of the casing 3 and is 15 then slid downwardly until the lowermost stop lug 25 upon the bottom of the tray contacts with the bar 26 which is in the position shown in Fig. 3 thereby positioning the first or foremost of the receptacles 39 immediately beneath the opening 2 of the spout 1, whereby a portion of the material traveling through the spout 1 in the direction of the arrow will drop through the opening 2 in the bottom of the spout 1 and fill the first 20 receptacle. This receptacle after being filled will remain stationary for a period of time, whereupon the driving wheel or disk 33 which is traveling slowly in the direction of the arrow will gradually move the locking 25 and releasing bar 26 to the neutral position shown in Fig. 5 until the bar 26 reaches the position shown in Fig. 4, whereby the locking lug 25 will be released and pass through the slot or gain 29 of the bar 26 thus allowing the tray to move downwardly by 30 gravity until the foremost locking lug 24 at the opposite side of the bottom 20 of the tray contacts with the bar 26 checking the downward movement of the tray and positioning the next succeeding or second receptacle 39 beneath the opening 2 of the spout 1, whereby the material that has previously 35 remained in the opening 2 after the filling of the first receptacle will now drop in the second receptacle, due to the divergent character of the side walls of the opening 2, and the filling operation of the second receptacle resumed. The tray again remains stationary while the bar 26 returns to the neutral position shown in Fig. 5, the wrist pin 32 of the wheel or disk 33 being in this instance in its lowermost position and opposite to that shown in Fig. 5, and until the bar 26 resumes the position shown in Fig. 3 for releasing the foremost lug 24 which now passes through the slot or gain 28 of the bar 26 allowing the tray to again slide downwardly until the second lug 25 contacts with the bar 26 for positioning the third empty receptacle beneath the opening 2 of the spout 1 to be also filled and as indicated in Fig. 2. These successive steps in the operation continue until all of the receptacles carried by the tray have been filled, whereupon the tray

with its filled receptacles is removed through the lower door 10, after the last locking lug has been released by the bar 26, and the contents of the receptacles or sample boxes 39 may be inspected for determining the various grades of the material which has passed 65 through the spout 1 within a specified period of time.

The casing 3, the tray, and the sample receptacles or boxes 39, as well as the housing 16 are preferably formed of sheet metal, the 75 casing 3 being secured upon the under side of the spout 1 so that the opening 2 of the spout 1 will be positioned substantially midway between the ends of the casing 3 which is of sufficient length to be slightly more 80 than twice the length of the tray, which tray is formed of a length for containing any desired number of sample boxes of any suitable and desired size, the stop lugs upon the tray being equal in number to the number 85 of sample boxes employed, and the operation of the locking and releasing bar 26 may be so timed that a sample may be taken at any intervals of time ranging from five minutes to one hour or longer during the conveying 90 crushing or grinding operation of the mill or the like for discharging the material through the spout 1.

It is to be understood, of course, that the 95 length of the casing 3 and the tray and the number of sample boxes used will vary in accordance with the number of samples taken within a given period, however, the positions of the locking and releasing bar 26 are shown in the drawings for taking a 100 sample every thirty minutes which is the usual preferred time, the driving wheel or disk 33 completing a revolution once every hour and which is preferably driven through the medium of the worm gear 36 and the 105 worm 37, the shaft 38 of the worm 37 may be suitably connected with any time mechanism such as a clock positioned within the housing 16 or may be suitably connected by a belt or cable with a pulley or shaft making 110 a predetermined number of revolutions per minute, there being, of course, suitable gear connections interposed between the time mechanisms and the shafts 38 to provide against excess speed or too slow speed, and 115 to change the time or intervals for taking the samples the worm gear connection between the shaft 38 and the shaft 34 may be efficiently adjusted by the substitution of other worm gear connections of different 120 sizes and differently timed for the worm gear 36 and the worm 37.

By the provision of the door 13 in the bottom of the casing 3 access may be readily had to the interior of the casing 3 for adjusting the position of the tray therein when desired which can be readily accomplished by bending the locking lugs 24 and 25 for

passing the bar 26, the lugs being sufficiently flexible for this purpose. The door 17 permits access into the interior of the housing 16 for adjusting the timing mechanism or for 5 any other desired purpose, and while I have shown the respective doors secured in closed position through the medium of spring catches or spring latches, any suitable locking devices may be employed for preventing 10 access to the interior of the device by unauthorized persons to thereby prevent tampering with the device by such persons.

Having described my invention, what I claim as new and desire to secure by Letters 15 Patent, is:

1. In a device of the character described, the combination with an inclined spout for conveying a material therethrough and provided with an orifice in its under side, of a 20 casing secured upon said spout and extending for a distance at either side of said orifice, a tray for traveling within said casing, a plurality of receptacles within said tray for receiving a sample of said material 25 through said orifice when positioned therebeneath, and means upon said tray coöperating with means within said casing to provide for the intermittent travel of said tray at predetermined periods of time.
2. In a device of the character described, the combination with an inclined spout for conveying a material therethrough and provided with an orifice in its under side and having divergent walls, of an elongated 30 casing secured to the under side of said spout beneath said orifice, a tray slidably mounted within said casing and adapted to travel therein from end to end, a plurality of receptacles carried by said tray adapted 35 to be positioned successively beneath said

orifice for obtaining various samples from said material during its course through said spout, lugs upon said tray, and a bar operating within said casing and coacting with said lugs of said tray for alternately checking and releasing said tray during its travel within said casing at predetermined periods of time.

3. In a device of the character described, the combination with a spout for conveying a material therethrough and provided with a transverse orifice in its under side having downwardly diverging side walls, of an elongated casing secured to the under side of said spout beneath said orifice, ribs formed at the inner sides of the side walls of said casing, a tray provided with flanges upon its upper edges for slidably engaging the ribs of said casing and adapted to gravitate therethrough, a plurality of receptacles positioned in succession within said tray in juxtaposition to each other for receiving a sample of the material in said spout through said orifice when positioned therebeneath, alternately staggered lugs upon the bottom 65 of said tray, a bar operating within said casing provided with means for alternately engaging and releasing said alternate lugs of said tray for controlling the movements of said tray, and means for operating said bar at a predetermined rate of speed for positioning a receptacle beneath said orifice at predetermined intervals.

In testimony whereof I have signed my name to this specification in the presence of two subscribing witnesses.

SEWARD E. COGSWELL.
